ASSIGNORS TO THE NATIONAL ACME COMPANY, OF CLEVELAND, OHIO, A COR-
PORATION OF OHIO.

CENTRIFUGAL CLARIFYING SEPARATOR.

Application filed July 25, 1927. Serial No. 208,209.

Our invention relates to a new and useful centrifugal clarifying separator and more particularly to a separator whereby commingled liquids of different densities and specific gravities, as well as of different consistencies and viscosities may be effectively and accurately separated.

Our invention further relates to a centrifugal separator of this general character, particularly designed for the separation of commingled liquids of different densities, where the difference in densities is relatively small, that is, for the separation of such commingled liquids being heretofore very difficult, if not impossible, of accomplishment, on a large commercial scale.

Our invention further relates to a device of this general character which in addition to separating commingled liquids also simultaneously clarifies or filters the same, thus producing pure and clear distinct liquids from an impure mixture or emulsion.

Our invention further relates to a centrifugal liquid separator of a relatively large volume capacity and one which may be run continuously for relatively long periods of time, without frequent cleaning or dismantling.

To the above ends, our invention consists of a suitable casing or housing, a central bowl rotatably disposed therein, a plurality of concentric cylinders positioned within said bowl and forming a series of concentric, intercommunicating compartments, an inlet leading into said bowl for the admission of the liquids to be clarified and separated, outlets for the separated, clarified liquids communicating with the respective compartments in said bowl, adjustable driving means for rotating said bowl and its adjuncts, and means for stopping the rotation of said bowl at will.

Our invention further consists of means for firmly securing the bowl in position while the same is rotated, and novel means for removing the bowl from the casing for the purposes of cleansing and repair.

Our invention further consists in a clarifying separator which is compact and strong and which is easily dismantled or assembled, there being a maximum number of detachable parts which can be easily and quickly assembled.

In the accompanying drawings: Fig. 1,

represents an end elevation of a clarifying separator embodying our invention. 55

Fig. 2, represents a vertical section of a clarifying separator embodying our invention, certain parts being shown in elevation.

Figure 3, represents a fragmentary, sectional view of the upper portion of Fig. 2, 60 showing the detailed construction.

Figure 4, represents a plan view of the bifurcated lever shown in the lower portion of Fig. 2.

Figure 5, represents a bottom plan view 65 of the bottom plate shown in the lower portion of Fig. 2.

Fig. 6, represents on a reduced scale a top plan view of the upper disc shown in Fig. 3.

Fig. 7, represents on a reduced scale, a fragmentary perspective view of the upper disc and superimposed collar shown in Figure 3. 70

For the purpose of illustrating our invention, we have shown in the accompanying drawings one form thereof which is at present preferred by us, since the same has been found in practice to give satisfactory and reliable results, although it is to be understood that the various instrumentalities of which our invention consists can be variously arranged and organized and that our invention is not limited to the precise arrangement and organization of the instrumentalities as herein shown and described. 75

Referring to the drawings, in which like reference numerals indicate corresponding parts, 1 designates a clarifying separator embodying our invention comprising a casing or housing 2 having a suitable support or base 3. 4 designates a bowl mounted within the casing 2 and having the lower base plate or disc 7 and the upper disc or cap member 6 which has the vertical, cylindrical extension 8. To the outside of the casing 2 is secured a sliding bracket 9 on which is mounted the motor 10 having the drive shaft 11 which carries the hub 12, on which is detachably secured a driving pulley 13 by means of the nuts 14. The bracket 9 may be vertically adjusted with respect to the casing 2 by means of the hand wheel 15 coacting with the screw threaded member 16 which is guided in the stationary bracket 17 suitably secured to the lower portion of the casing 2. A belt 18 passes over the driving pulley 13, the idler pulley 19 secured to the bracket 9, and over the 100 105

idler pulleys 20 secured to the lower portion of the casing 2, onto the spindle pulley 21, fast on the spindle 22 which is provided at its upper portion with the pins 23 which in turn engage notches 24 in the bottom of the disc or plate 7 to revolve the bowl 4 mounted thereon, the head 25 of the spindle 22 being engaged by the socket 26 of said bottom plate 7. A brake lever 27 operated by an external handle member 28 is provided in proximity to the bottom plate 7 of the bowl 4 and is adapted to bear upwardly on the brake shoe 29 which in turn acts on said bottom plate 7 to stop the rotation of the bowl 4. The brake lever 27 is provided with a stop lug 30 adapted to abut against the inner face of the casing 2, to limit the upward movement of said brake lever 27 to prevent any possible displacement of the bowl 4 when the brake is applied. A lever arm 31, pivoted at 32, is provided with the cam 33, adapted to coact with the lever arm 34 pivoted at 35 and provided with the bifurcated end 36 which in turn engage corresponding openings 37 in the bottom plate 25 or disc 7, to raise the bowl 4 by disengaging the head 25 of the spindle 22 from the socket 26 and by disengaging the pins 23 from the holes 24 in the lower side of the disc or base plate 7 of the bowl 4. The door 5 may then 30 be swung open with the bowl 4 supported on the bifurcated ends 36 of the lever 34 and secured to the inside of the door 5 by the strap or ring 38 which prevents said bowl from falling.

35 On the top of the casing 2 is detachably mounted the sectional cover 39 comprising a series of superimposed pans 40, 41, and 42, said pans being detachably mounted upon each other and being adapted to serve as receptacles for the separated and clarified liquids as well as for any overflow emerging from the interior of the casing 2. The pans 40, 41, and 42 are also provided with the detachable nozzles or discharge outlets 43, 44, and 45 respectively, as will be understood from Fig. 2. A gravity oil feed 46 is mounted on the bearing pan 40, whereby oil is supplied to the interior bearing and other working parts of the clarifying separator through the channel 47. Within the bowl 4 is positioned a cylinder 48 mounted upon the lower disc or plate 49 which has a plurality of radial ports 50, said cylinder 48 being secured at its upper end to an upper disc 51 of a relatively larger diameter than said lower disc 49. Within the cylinder 48 is provided a screen or filter member 52 also secured to said lower and upper discs 49 and 51 respectively, as will be understood from Fig. 2. Within the screen 52 is positioned the inner tubular member 53 secured at its lower end to the disc 49 and extending upwardly through the casing 2 and into the sectional cover 39 in proximity to and parallel with the vertical extension 8 of the cap member 6, as will be understood from

Fig. 2. Into the tubular member 53 extends the inlet tube 54, the upper end of which communicates with the inlet 55 having the stop valve 56 and the lower end of which is provided with a discharge nozzle portion 57. Intermediate the upright extension 8 of the cap 6 and the inner tubular member 53 is positioned cylindrical sleeve 58 secured at its lower end to the upper disc 51 and at its upper end to the collar 59. The inverted bearing 75 cap 60 engages the pendant flange 61 of the bottom 62 of the pan 40 while the horizontal extensions 63 and the vertical extension 64 respectively thereof are adapted to bear against the upright extension 8 of the cap 6. Within 80 the inverted bearing cap or collar 60 is disposed the inner sliding collar 66 in which is positioned the spring 67, said sliding collar being adapted to take up the play and vibration resulting from the rapid rotation of the 85 bowl 4 and its adjuncts within the casing 2 and the sectional cover 39. A door 79 is provided in the lower portion of the casing 2 through which access may be had to the spindle 22 and its adjuncts.

90 In Fig. 3, we have shown on an enlarged scale a detail view of the upper portion of Fig. 2 in which a dam or distance ring 80, supported on the annular shoulder 81 and held in position by the collar 82, extends into the 95 opening 73 to regulate the width or radius of said opening according to the viscosity or density of the fluid being treated. Thus, if a very heavy, dense fluid, like fuel or crude oil, is being treated, the distance ring 80 is 100 altogether dispensed with, while distance rings 80 of varying sizes may be employed when liquids of less density such as lubricating oil or the like are being treated.

105 The operation is as follows:

The mixed fluids, say, oil and water, to be separated and clarified are introduced through the inlet 55 into the tube 54 from which they emerge through the nozzle 57 into the tube 53 which is secured at its lower end 110 to the disc or plate 49 which has the radial ports 50. The fluid flows through said ports 50 into the outer compartment 69 intermediate the bowl 4 and the inner casing 48. As the bowl is rapidly rotated in the manner 115 above described the mixed oil and water introduced into the interior of said bowl are gradually separated by centrifugal force and the heavier or denser liquids, that is, that having the higher specific gravity, collects in 120 the outer portion of the compartment 69, that is, at a maximum distance from the axis of rotation while the lighter liquids having a lower specific gravity collect in the inner portion of said compartment. Thus the water 125 or heavier liquid forms an outer circular layer adjacent the inner surface of the bowl 4 while the oil or lighter material forms an inner circular layer adjacent the outer surface of the inner casing 48 with a "neutral" 130

zone" formed between said layers of water and oil. As additional fluid mixture is introduced into the tube 53 the separated layers of water and oil rise in the compartment 69 until the opening 70 in the casing 48 is reached. The inner column, or the column of oil, now passes through the opening 70 into the compartment 71 intermediate the screen 52 and the casing 48. The water, on the other hand, emerges through the ports 72 in the upper disc 51 and the collar 72^x and rises in the opening 73 intermediate the upper extension 8 of the cap 6 and cylindrical sleeve 58 until it emerges through the upper opening 74 into the lowermost pan 40 and out through the nozzle 43. The oil entering the compartment 71 through the opening 70 is strained or filtered through the screen 52 into the compartment 75, and rises in the opening 76 intermediate the tubular member 53 and the cylindrical sleeve 58 until it flows out through the opening 77 into the pan 41 and out through the nozzle 44. Since the initial separation of the water and the oil which takes place in the compartment 69 is not quite perfect, that is, since the oil entering the compartment 71 through the opening 70 and ultimately the compartment 75 through the screen 52 may still have a certain percentage of water, openings 68 are provided in the inner casing 48 through which any water separated from the oil in the compartments 71 and 75 may flow back into the compartment 69 where the outer layer of water is originally formed. An opening 78 is provided intermediate the sleeve 83 which is secured at its lower end to the upper end of the inner tubular member 53 and the inlet tube 54 through which any excess fluid introduced into the bowl 4 may escape. Thus, if the screen 52 or any of the openings in the bowl 4 are clogged so that the normal flow of the fluid is retarded, the opening 78 provides an outlet through which said fluid may escape into the pan 42 and out through the overflow nozzle 45.

To facilitate the use of a relatively large bowl 4 and its adjuncts, with the attendant advantages of less frequent cleaning, and of more perfect separation and clarification of the mixed liquids, we have provided means for the easy manipulation of the bowl 4 and its adjuncts. Thus, when it is desired to clean the bowl 4 or to interchange any of the screens or cylinders therein, it is merely necessary to remove the pans 40, 41, and 42, forming the sectional cover 39 and then to raise the bowl 4 from engagement with the pins 23 and the head 25 of the spindle 22 by means of the lever 31 and its adjuncts in the manner shown and described. The door 5 is then swung open with bowl 4 resting on the bifurcated ends 36 of the lever 34 and secured to the inside of the door 5 by the ring or strap 38, the bifurcated ends 36 engaging the notches 37 in the

bottom of the plate 7 serving to prevent the rotation of the bowl 4 while the cap 6 thereof is unscrewed. The screen 52 and the cylinder 48 can then be removed for replacement and repair. When it is desired to replace the bowl 4 in position it is merely necessary to close the door and then to lower the handle 31 (into the position shown in Fig. 2) thus withdrawing the bifurcated ends 36 from engagement with the notches 37 and the holes 24 as well as the socket 26 again engage the pins 23 and the head 25 of the spindle 22 and the bowl is again in the position shown in Fig. 2 and is again ready for use.

By detachably mounting the drive pulley 13 on the spindle 12 permanently keyed to the drive shaft 11 we are enabled to employ drive pulleys of different sizes to vary the speed at which the bowl 4 is rotated, when a single speed motor is used.

It will now be apparent that we have devised a novel and useful construction of centrifugal clarifying separator which embodies the features of advantage enumerated as desirable in the statement of the invention and the above description and while we have in the present instance shown and described the preferred embodiment thereof which has been found in practice to give satisfactory and reliable results, it is to be understood that the same is susceptible of modification in various particulars without departing from the spirit or scope of the invention or sacrificing any of its advantages.

Having thus described our invention, what we claim as new and desire to secure by Letters Patent is:—

1. In a device of the character stated, a housing, a bowl rotatably mounted therein, adjustable means for driving said bowl, a plurality of concentric, communicating cylinders within said bowl forming a series of compartments intercommunicating with each other and with said bowl, a screen in one of said compartments, a sectional cover for said bowl and housing, comprising a series of superimposed pans, discharge outlets for said pans and an intake inlet for the upper end of said bowl, there being openings leading from the upper ends of said compartments into said pans.

2. In a device of the character stated, a housing, a bowl rotatably mounted therein, means for driving said bowl, a plurality of concentric cylinders within said bowl forming a series of annular, concentric compartments intercommunicating with each other and with said bowl, screening means in one of said compartments, a sectional cover for said bowl and housing, comprising a series of superimposed pans, discharge outlets for said pans, there being corresponding exit openings leading from the upper portions of said respective compartments to said respective pans, adjustable means to vary the ra-

radius of one of said exit openings, and an intake inlet for the upper end of said bowl communicating with the central one of said compartments.

5. 3. In a device of the character stated, a housing, a bowl rotatably mounted therein, means for driving said bowl, sectional covers for said bowl and housing, comprising a series of superimposed pans, discharge 10 spouts for said pans, manually operable means for disengaging said bowl from said driving means, and manually operable means for stopping the rotation of said bowl, said bowl comprising inner and outer concentric 15 cylinders the outer of said cylinders being permanently secured to the base of said bowl, a detachable cover for said bowl, a series of intermediate concentric cylinders secured to upper and lower discs of different diameters 20 within said bowl and forming concentric compartments intercommunicating with each other and with said bowl, said discs having ports therein, screening means within one of said compartments, and an intake inlet for 25 the upper portion of said bowl, there being exit openings leading from said compartments to said pans.

4. In a clarifying separator, a housing, a sectional cover for said housing comprising a 30 series of superimposed pans, discharge spouts for said pans, and a bowl rotatably mounted within said housing, said bowl comprising an inner, central cylinder and an outer cylinder, said outer cylinder being permanently se- 35 cured to the base of said bowl, said inner, central cylinder extending upwardly through said housing into said sectional cover, an intake inlet for the upper portion of said central cylinder, a cover for said bowl detach- 40 ably mounted on said outer cylinder, intermediate communicating cylinders within said bowl detachably secured to lower and upper discs and forming concentric, intercommuni- 45 cating compartments, the lower of said discs being of a lesser diameter than said upper disc and having radial ports therein leading from said central cylinder to the outermost of said compartments, there being exit open- 50 ings leading from said respective concentric compartments to said respective pans.

5. In a device of the character stated, a housing, a bowl therein comprising an inner central cylinder and an outer cylinder, said outer cylinder being permanently secured to 55 the base of said bowl, said inner central cylinder extending upwardly through said housing into a sectional pan-formed cover, an intake inlet for the upper portion of said central cylinder, a sectional detachably mounted, 60 pan-formed cover for said bowl and housing, intermediate cylinders within said bowl detachably secured to lower and upper discs and forming concentric, intercommunicating compartments, said lower disc being of a 65 lesser diameter than said upper disc and both

of said discs having radial ports therein leading to and from the outermost of said compartments, there being exit openings leading from said respective concentric compartments to said respective pans.

6. In a device of the character stated, a housing, a bowl therein comprising an inner central cylinder and an outer cylinder, said outer cylinder being permanently secured to the base of said bowl, said inner, central cylinder extending upwardly through said housing into a sectional pan-formed cover, an intake inlet for the upper portion of said central cylinder, a sectional detachably mounted, pan formed cover for said bowl and housing, 75 intermediate communicating cylinders within said bowl detachably secured to lower and upper discs and forming concentric, intercommunicating compartments, screening means in one of said compartments, said lower disc being of a lesser diameter than said upper disc and both of said discs having radial ports therein leading to and from the outermost of said compartments, there being exit openings leading from said respective 80 concentric compartments to said respective pans, and means for regulating the size of one of said exit openings.

7. In a clarifying separator, a housing, a sectional cover for said housing comprising a series of superimposed pans, discharge spouts for each of said pans, and a bowl rotatably mounted within said housing, said bowl comprising an inner, central cylinder and an outer cylinder, said outer cylinder being permanently secured to the base of said bowl, said inner, central cylinder extending upwardly through said housing into said sectional cover, an intake inlet for the upper portion of said central cylinder, intermediate communicating cylinders within said bowl, detachably secured to lower and upper discs and forming concentric, intercommunicating compartments therebetween, said lower disc being of a lesser diameter than said upper disc and both of said discs having ports therein leading to and from the outermost of said compartments, a cover for said bowl detachably mounted on the top of said outer cylinder and having an upper vertical extension, and a cylindrical sleeve intermediate said extension and said inner central cylinder, there being openings leading from said concentric compartments to said pans.

8. In a device of the character stated, a housing, a bowl rotatably mounted therein, adjustable means for driving said bowl, a plurality of concentric cylinders within said bowl forming a series of annular, concentric compartments intercommunicating with each other and with said bowl, screening means in one of said compartments, a sectional cover for said bowl and housing, comprising a series of superimposed pans, discharge outlets for said pans, there being corresponding con- 12 13

- centric exit openings leading from the upper portions of said respective compartments to said respective pans, adjustable means to vary the size of one of said exit openings, an intake 5 inlet for the upper end of said bowl communicating with the central one of said compartments, and means common to the upper portion of said bowl and the lower portion of said sectional cover for yieldably guiding said 10 bowl and its adjuncts in position while the same are rotated.
9. In a device of the character stated, a housing, a bowl rotatably mounted therein, adjustable means for driving said bowl, a 15 plurality of compartments in said bowl intercommunicating with each other and with said bowl, a sectional cover for said bowl and housing comprising a series of superimposed pans, discharge outlets for said pans, there 20 being openings leading from said compartments into said pans, means for varying the size of one of said openings, an intake inlet for said bowl, screening means in one of said compartments, and means for yieldably retaining and guiding the upper portion of 25 said bowl and its adjuncts while the bowl is rotated.
10. In a device of the character stated, a bowl comprising a series of annular compartments, means for causing the liquid treated 30 therein to travel in opposite directions, a ported disk in the upper end of said bowl and overhanging the outer portion of the outer compartment and opening adjacent to the outer wall thereof, and a cover for said bowl having an upward tubular extension within 35 which an exit passage for said liquid is formed.
11. In a device of the character stated, a bowl comprising a series of annular compartments, means for causing the liquid treated 40 therein to travel in opposite directions, and a radially ported disk in the upper end of said bowl and overhanging the outer portion of the outer compartment and opening adjacent to the outer wall thereof.
12. In a device of the character stated, a bowl comprising a series of annular compartments, means for causing the liquid treated 45 therein to travel in opposite directions, and a ported disk in the lower end of said bowl and opening adjacent to the inner wall of said outer compartment.
13. In a device of the character stated, a bowl comprising a series of annular compartments, means for causing the liquid treated 55 therein to travel in opposite directions, a radially ported disk in the upper end of said bowl and overhanging the outer portion of the outer compartment and opening adjacent to the outer wall thereof, and a radially ported disk in the lower end of said bowl and opening adjacent to the inner wall of said outer compartment.
14. In a device of the character described, 60 a bowl comprising a plurality of annular intercommunicating compartments, means for causing the liquid to travel in opposite directions therein, a pair of ported disks in said bowl adjacent to the upper and lower ends thereof and both opening into the outer compartment, and extended passageways above the bowl and leading from said several compartments. 70
15. In a device of the character described, a bowl comprising a plurality of annular intercommunicating compartments, means for causing the liquid to travel in opposite directions therein, screening means in one of said compartments, a pair of ported disks in 75 said bowl adjacent to the upper and lower ends thereof and both opening into the outer compartment, and extended passageways above the bowl and leading from said several compartments. 80
16. In a device of the character described, a bowl comprising a plurality of annular intercommunicating compartments, means for causing the liquid to travel in opposite directions therein, a pair of disks in said bowl adjacent to the upper and lower ends thereof, one of greater diameter than the other and each having radially opening ports, and both opening into the outer compartment, and extended passageways above the bowl 85 and leading from said several compartments. 90
17. In a device of the character described, a bowl comprising a plurality of annular intercommunicating compartments, means for causing the liquid to travel in opposite directions therein, a pair of ported disks in said bowl adjacent to the upper and lower ends thereof and both opening into the outer compartment, extended passageways above the bowl 95 and leading from said several compartments, and sectional, superimposed and spouted pan-formed chambers for said bowl into which said extended passageways open. 100
18. In a device of the character described, a bowl comprising a plurality of annular intercommunicating compartments, means for causing the liquid to travel in opposite directions therein, a pair of ported disks in said bowl adjacent to the upper and lower ends thereof and both opening into the outer compartment, extended passageways above the bowl and leading from said several compartments, and means in one of said extended passageways for regulating the area thereof. 110
19. In a device of the class described, a bowl for separating and purifying liquids comprising a chamber-forming outer cylinder having a bottom and a cover, a pair of disks located adjacent to the top and bottom of the cylinder, the top disk having greater 115 diameter than said bottom disk and each having radial ports communicating with the chamber of said cylinder, the radial ports of the top disk communicating with the chamber of the cylinder nearer the outer wall than the radial ports of the lower disk, an inner 120
- 130

cylinder connected with and communicating with the radial ports of the lower disk, and a plurality of intermediate intercommunicating cylinders carried by said disks and including screening means.

20. In a device of the class described, a bowl for separating and purifying liquids comprising a chamber-forming outer cylinder having a bottom and a cover, a pair of 10 disks located adjacent to the top and bottom of the cylinder, the top disk having greater diameter than said bottom disk and each having radial ports communicating with the chamber of said cylinder, the radial 15 ports of the top disk communicating with the chamber of the cylinder nearer the outer wall than the radial ports of the lower disk, an inner cylinder connected with and communicating with the radial ports of the lower 20 disk, and a plurality of intermediate intercommunicating cylinders carried by said disks and including screening means, the ports of the lower disk opening substantially in line with the lower end of one of said 25 intermediate cylinders and the ports of the upper disk opening beyond said cylinder.

21. In a device of the class described, a bowl for separating and purifying liquids comprising a chamber-forming outer cylinder having a bottom and a cover, a pair of 30 disks located adjacent to the top and bottom of the cylinder, the top disk having greater diameter than said bottom disk and each having radial ports communicating with the 35 chamber of said cylinder, the radial ports of the top disk communicating with the chamber of the cylinder nearer the outer wall than the radial ports of the lower disk, an inner cylinder connected with and communicating with the radial ports of the lower disk, and a plurality of intermediate intercommunicating cylinders carried by said disks and including screening means, the radial 40 ports of the lower disk having greater diameter than the radial ports of the upper disk.

22. In a device of the class described, a bowl for separating and purifying liquids comprising a chamber-forming outer cylinder having a bottom and a cover, a pair of 50 disks located adjacent to the top and bottom of the cylinder, the top disk having greater diameter than said bottom disk and each having radial ports communicating with the 55 chamber of said cylinder, the radial ports of the top disk communicating with the chamber of the cylinder nearer the outer wall than the radial ports of the lower disk, an inner cylinder connected with and communicating 60 with the radial ports of the lower disk, and a plurality of intermediate intercommunicating cylinders carried by said disks and including screening means, the ports of the 65 lower disk opening substantially in line with the lower end of one of said intermediate cylinders and the ports of the upper disk opening beyond said cylinder.

inders and the ports of the upper disk opening beyond said cylinder, said intermediate cylinder having ports adjacent to its upper end.

23. In a device of the class described, a 70 bowl for separating and purifying liquids comprising a chamber-forming outer cylinder having a bottom and a cover, a pair of disks located adjacent to the top and bottom of the cylinder, the top disk having greater 75 diameter than said bottom disk and each having radial ports communicating with the chamber of said cylinder, the radial ports of the top disk communicating with the chamber of the cylinder nearer the outer wall 80 than the radial ports of the lower disk, an inner cylinder connected with and communicating with the radial ports of the lower disk, and a plurality of intermediate intercommunicating cylinders carried by said disks 85 and including screening means, the ports of the lower disk opening substantially in line with the lower end of one of said intermediate cylinders and the ports of the upper disk opening beyond said cylinder, said intermediate 90 cylinder having two sets of spaced ports adjacent to its upper end.

24. In a device of the class described, a bowl for separating and purifying liquids comprising a chamber-forming outer cylinder having a bottom and a cover, said cover having an upward tubular extension, a pair of disks located adjacent to the top and bottom of the cylinder, the top disk having greater diameter than said bottom disk and 95 each having radial ports communicating with the chamber of said cylinder, the radial ports of the top disk communicating with the chamber of the cylinder nearer the outer wall than the radial ports of the lower disk, an inner 100 cylinder connected with and communicating with the radial ports of the lower disk and extending into said tubular extension, an intermediate cylinder connected with said top disk and located between said extensions and 105 forming passageways therebetween, one opening into the outer cylinder and the other into an intermediate cylinder, and a plurality of intermediate intercommunicating cylinders 110 carried by said disks and including screening means.

25. In a device of the class described, a bowl for separating and purifying liquids comprising a chamber-forming outer cylinder having a bottom and a cover, said cover having an upward tubular extension, a pair of disks located adjacent to the top and bottom of the cylinder, the top disk having greater diameter than said bottom disk and each having radial ports communicating with the chamber of said cylinder, the radial ports of the top disk communicating with the chamber of the cylinder nearer the outer wall than the radial ports of the lower disk, an inner 120 cylinder connected with and communicating 125 with the radial ports of the lower disk, and a plurality of intermediate intercommunicating cylinders carried by said disks and including screening means.

with the radial ports of the lower disk and extending into said tubular extension, an intermediate cylinder connected with said top disk and located between said extensions and

5 forming passageways therebetween, one opening into the outer cylinder and the other into an intermediate cylinder, a plurality of intermediate intercommunicating cylinders carried by said disks and including screening means, and means located in said tubular extension for varying the area thereof.

26. In a device of the class described, a bowl for separating and purifying liquids comprising a chamber-forming outer cylinder having a bottom and a removable cover provided with an upward tubular extension, a pair of disks located adjacent to the top and bottom of said outer cylinder, the top disk having larger diameter than the bottom disk and each having radial ports, an inner cylinder connected with and communicating with the radial ports of the lower disk and projecting into the tubular extension of the removable cover, an intermediate cylinder between said tubular extension and inner cylinder and forming passages therebetween, an intermediate cylinder carried by said disks with the radial ports of the lower disk opening into the chamber of the outer cylinder adjacent to the wall of said intermediate cylinder and with the ports of the upper disk opening into the chamber of the outer cylinder beyond the wall of the intermediate cylinder and adjacent to the wall of the outer cylinder, said intermediate cylinder having a plurality of ports located adjacent to the top thereof, and a screening cylinder carried by said disks intermediate said inner and intermediate cylinders.

40 27. In a device of the class described, a
bowl for separating and purifying liquids
comprising a chamber-forming outer cylinder
having a bottom and a removable cover pro-
vided with an upward tubular extension, a
45 pair of disks located adjacent to the top and
bottom of said outer cylinder, the top disk
having larger diameter than the bottom disk
and each having radial ports, an inner cylin-
der connected with and communicating with
50 the radial ports of the lower disk and pro-
jecting into the tubular extension of the re-
movable cover, an intermediate cylinder be-
tween said tubular extension and inner cyl-
inder and forming passages therebetween, de-
55 tachable means positioned within the tubular
extension for varying the area of the passage
thereof, an intermediate cylinder carried by
said disks with the radial ports of the lower
disk opening into the chamber of the outer
60 cylinder adjacent to the wall of said interme-
diate cylinder and with the ports of the up-
per disk opening into the chamber of the outer
cylinder beyond the wall of the intermediate
cylinder and adjacent to the wall of the outer
65 cylinder, said intermediate cylinder having a

plurality of ports located adjacent to the top thereof, and a screening cylinder carried by said disks intermediate said inner and intermediate cylinders.

28. In a device of the class described, a bowl for separating and purifying liquids comprising a chamber-forming outer cylinder having a bottom and a removable cover provided with an upward tubular extension, a pair of disks located adjacent to the top and bottom of said outer cylinder, the top disk having larger diameter than the bottom disk and each having radial ports, an inner cylinder connected with and communicating with the radial ports of the lower disk and projecting into the tubular extension of the removable cover, an intermediate cylinder between said tubular extension and inner cylinder and forming passages therebetween, detachable means positioned within the tubular extension for varying the area of the passage thereof, an intermediate cylinder carried by said disks with the radial ports of the lower disk opening into the chamber of the outer cylinder adjacent to the wall of said intermediate cylinder and with the ports of the upper disk opening into the chamber of the outer cylinder beyond the wall of the intermediate cylinder and adjacent to the wall of the outer cylinder, said intermediate cylinder having a plurality of ports located adjacent to the top thereof, a screening cylinder carried by said disks intermediate said inner and intermediate cylinders, and sectional, superimposed, pan-formed chambers in communication with various passages of said bowl.

29. In a device of the class described, a bowl for separating and purifying liquids comprising a chamber-forming outer cylinder having a bottom and a removable cover provided with an upward tubular extension, a pair of disks located adjacent to the top and bottom of said outer cylinder, the top disk having larger diameter than the bottom disk and each having radial ports, an inner cylinder connected with and communicating with the radial ports of the lower disk and projecting into the tubular extension of the removable cover, an intermediate cylinder between said tubular extension and inner cylinder and forming passages therebetween, detachable means positioned within the tubular extension for varying the area of the passage thereof, an intermediate cylinder carried by said disks with the radial ports of the lower disk opening into the chamber of the outer cylinder adjacent to the wall of said intermediate cylinder and with the ports of the upper disk opening into the chamber of the outer cylinder beyond the wall of the intermediate cylinder and adjacent to the wall of the outer cylinder, said intermediate cylinder having a plurality of ports located adjacent to the top thereof, a screening cylinder 105 110 115 120 125 130

der carried by said disks intermediate said inner and intermediate cylinders, sectional, superimposed, pan-formed chambers in communication with various passages of said bowl, means for rotating said bowl, and means for separating the bowl from its rotating means and swinging the same laterally relatively thereto.

30. In a device of the class described, a bowl for separating and purifying liquids comprising a chamber-forming outer cylinder having a bottom and a removable cover provided with an upward tubular extension, a pair of disks located adjacent to the top and bottom of said outer cylinder, the top disk having larger diameter than the bottom disk and each having radial ports, an inner cylinder connected with and communicating with the radial ports of the lower disk and projecting into the tubular extension of the removable cover, an intermediate cylinder between said tubular extension and inner cylinder and forming passages therebetween, detachable means positioned within the tubular extension for varying the area of the passage thereof, an intermediate cylinder carrier by said disks with the radial ports of the lower disk opening into the chamber of the outer cylinder adjacent to the wall of said intermediate cylinder and with the ports of the upper disk opening into the chamber of the outer cylinder beyond the wall of the intermediate cylinder and adjacent to the wall of the outer cylinder, said intermediate cylinder having a plurality of ports located adjacent to the top thereof, a screening cylinder carried by said disks intermediate said inner and intermediate cylinders, sectional, superimposed, pan-formed chambers in communication with various passages of said bowl, means for rotating said bowl, means for separating the bowl from its rotating means and swinging the same laterally relatively thereto, and means for braking the bowl and in position to engage the same without separating the same from its rotating means.

31. In a device of the class described, a bowl for separating and purifying liquids comprising a chamber-forming outer cylinder having a bottom and a removable cover provided with an upward tubular extension, a pair of disks located adjacent to the top and bottom of said outer cylinder, the top disk having larger diameter than the bottom disk and each having radial ports, an inner cylinder connected with and communicating with the radial ports of the lower disk and projecting into the tubular extension of the removable cover, an intermediate cylinder between said tubular extension and inner cylinder and forming passages therebetween, an intermediate cylinder carried by said disks with the radial ports of the lower disk opening into the chamber of the outer cylinder adjacent to the wall of said intermediate cylinder and

with the ports of the upper disk opening into the chamber of the outer cylinder beyond the wall of the intermediate cylinder and adjacent to the wall of the outer cylinder, said intermediate cylinder having a plurality of ports located adjacent to the top thereof, a screening cylinder carried by said disks intermediate said inner and intermediate cylinders, a single speed motor for rotating said bowl, and means for adjusting the same relatively to the bowl, thereby to permit the speed of the bowl to be varied by interchangeable pulleys.

32. In a device of the class described, a bowl for separating and purifying liquids comprising a chamber-forming outer cylinder having a bottom and a removable cover provided with an upward tubular extension, a pair of disks located adjacent to the top and bottom of said outer cylinder, the top disk having larger diameter than the bottom disk and each having radial ports, an inner cylinder connected with and communicating with the radial ports of the lower disk and projecting into the tubular extension of the removable cover, an intermediate cylinder between said tubular extension and inner cylinder and forming passages therebetween, an intermediate cylinder carried by said disks with the radial ports of the lower disk opening into the chamber of the outer cylinder adjacent to the wall of said intermediate cylinder and with the ports of the upper disk opening into the chamber of the outer cylinder beyond the wall of the intermediate cylinder and adjacent to the wall of the outer cylinder, said intermediate cylinder having a plurality of ports located adjacent to the top thereof, a screening cylinder carried by said disks intermediate said inner and intermediate cylinders, a single speed motor for rotating said bowl, means for adjusting the same relatively to the bowl, thereby to permit the speed of the bowl to be varied by interchangeable pulleys, and means for separating the bowl from its rotating means and swinging the same laterally relatively thereto.

33. In a device of the character described, a housing, a bowl rotatably mounted therein, means for driving said bowl, means for engaging the bowl for separating it from its driving means, thereby to permit it to be swung laterally out of the housing, means for engaging the bottom of the bowl for braking the same without interfering with the connection thereof with its driving means, said bowl comprising a cylindrical casing having a bottom and a removable cover provided with a tubular, upward extension, a pair of disks within said casing and having radial ports, an inner cylinder carried by and communicating with the radial ports of the lower disk and extending into said tubular extension, an intermediate ported cylinder carried by said disks, and screening means car-

ried by said disks and located between said intermediate and inner cylinders.

34. In a device of the character described, a housing, a bowl rotatably mounted therein, means for driving said bowl, means for engaging the bowl for separating it from its driving means, thereby to permit it to be swung laterally out of the housing, means for engaging the bottom of the bowl for 5 braking the same without interfering with the connection thereof with its driving means, said bowl comprising a cylindrical casing having a bottom and a removable cover provided with a tubular, upward extension, a 10 pair of disks within said casing and having radial ports, an inner cylinder carried by and communicating with the radial ports of the lower disk and extending into said tubular extension, an intermediate ported cylinder 15 carried by said disks, screening means carried by said disks and located between said intermediate and inner cylinders, an intermediate cylinder between said tubular extension and inner cylinder and forming a plurality of 20 25 30 passages from the bowl, one in communication with the radial ports of the upper disk and the other in communication with the chamber around the inner cylinder, and means for supplying liquid to the inner cylinder.

35. In a device of the character described, a housing, a bowl rotatably mounted therein, means for driving said bowl, means for engaging the bowl for separating it from its driving means, thereby to permit it to be swung laterally out of the housing, means for engaging the bottom of the bowl for braking the same without interfering with the connection thereof with its driving means, said 35 40 45 50 55 60 bowl comprising a cylindrical casing having a bottom and a removable cover provided with a tubular, upward extension, a pair of disks within said casing and having radial ports, an inner cylinder carried by and communicating with the radial ports of the lower disk and extending into said tubular extension, an intermediate ported cylinder carried by said disks, screening means carried by said disks and located between said intermediate and inner cylinders, an intermediate cylinder between said tubular extension and inner cylinder and forming a plurality of 65 70 75 80 85 90 95 100 105 110 115 120 125 130 135 140 145 150 155 160 165 170 175 180 185 190 195 198 200 205 210 215 220 225 230 235 240 245 250 255 260 265 270 275 280 285 290 295 298 300 305 310 315 320 325 330 335 340 diameter and discharges the heavier of the two liquids through the radial ports of the disk of larger diameter.

41. In a device of the character described, 5 the combination of a rotating bowl for separating and purifying liquids having a plurality of annular ported compartments to cause the liquid to have an extended travel in opposite directions, screening means in one 10 of said compartments for purifying the liq-

uid, and a pair of disks in the bowl of different diameters and provided with radial ports, whereby the liquid enters through the radial ports of the disk of smaller diameter and discharges the heavier of the two liquids 15 through the radial ports of the disk of larger diameter.
